STUD STAMPING MACHINE

Stephen Straty, Milwaukee, Wis., assignor to
 Kilbourn Engineering Company, Milwaukee,
 Wis., a corporation of Wisconsin

Application August 19, 1946, Serial No. 691,618

6 Claims. (Cl. 101—4)

1

This invention relates to machines for stamping or marking articles with characters, letters or the like.

The principal object of the invention is to provide an improved machine for marking bolts, studs and the like which is easy to operate, and readily adaptable to a wide variety of lengths and sizes of studs with a minimum of time-consuming adjustments.

Another object of the invention is to provide a stud stamping machine which will uniformly mark the studs notwithstanding substantial variations in the actual dimensions of studs of the same general size.

Another object of the invention is to provide an improved marking machine which can be easily adjusted to mark bolts, studs and the like with characters or letters at either end or at both ends.

Another object is to provide a strong, sturdy machine of inexpensive and simple design which will operate indefinitely without breakdown or repairs.

A preferred embodiment of the invention is shown in the accompanying drawings in which:

Figure 1 is a side plan view of the machine;

Fig. 2 is a front plan view of the machine;

Fig. 3 is a top plan view of the machine;

Fig. 4 is a horizontal sectional view of the machine taken on line 4—4 of Figure 1;

Fig. 5 is a vertical section taken on a central plane passing forwardly and rearwardly through the machine;

Fig. 6 is a detailed sectional view showing the die and mandrel in the mid-course of the stamping action; and

Fig. 7 is a view similar to Fig. 6 showing the die and mandrel in the completed stamping position.

The machine, in general, comprises a circular horizontal table assembly 1 mounted on a base 2, a plurality of fixtures or bushings 3 circularly arranged on table assembly 1 and disposed vertically to receive studs 4 or the like and carry them for marking between a set of dies, and power means coordinated to operate the table assembly 1 and the dies to stamp either or both ends of the studs 4 as each passes therebetween.

The base 2 may consist simply of a metal frame 5 having a stationary mounting base 6 and braces 7 to hold the frame 5 upright and impart strength and rigidity to the frame.

The table assembly 1 comprises a circular metal plate or table 8 of suitable thickness fitted with holes 9 to receive fixtures such as bushings 3 in which the studs are carried for marking.

2

The holes 9 are circularly arranged about the center of the table near its periphery, and are equally spaced circumferentially of the table. The number of holes 9 should correspond with the number of bushings 3 used and the number of studs 4 to be marked with each rotation of the table 8. In the drawings twelve holes and an equal number of bushings 3 are shown mounted in the table 8 of assembly 1.

Four detent balls 10 circularly arranged about and near the center of table 8 are fitted in holes 11 drilled in table 8 and extend slightly beneath the table 8. Springs 12 within holes 11 position the balls 10 and are themselves secured within the holes 11 by plugs 13 fitted in the top of the table 8.

The table 8 is rotatively mounted so that it is supported by the four detent balls 10 which ride on the indexing table 14 and engage the ball 20 detent seats 15 in the table 14. The indexing table 14 is circular, of the same diameter as table 8, and rests upon the mounting bracket 16 extending forwardly of base 2 and bolted to the frame 5.

A pin 17 having a flange 18 at its upper end extends through the centers of tables 8 and 14 and is secured in a socket 19 in the table mounting bracket 16. The flange 18 secures table 8 and maintains the detent balls 10 in contact with table 14 and the ball detent seats 15. The lower end of pin 17 is secured in the socket 19 by means of set screws 20 which permit the easy removal of the table assembly.

The bushings 3 are cylindrical, hollow-cored 35 lengths of metal and are seated in the holes 9 of the table 8 to receive the studs 4 to be carried thereabout for marking. The bushings 3 should slide fit in the holes 9 and the studs 4 fit loosely within the cores of the bushings 3. As the table 40 8 rotates, the studs 4 should rest on end and slide around upon the upper surface of the indexing table 14.

The bushings 3 need only be long enough to properly hold the studs 4 upright for marking and should not be any longer than necessary for passing between the dies. The articles after being marked can be easily lifted from the bushings and removed by dropping the same through a hole in plate 14 beneath one or more subsequent index positions for the articles, as shown in dotted lines in Fig. 3.

When setting up the machine for marking studs of a certain size, a complete set of bushings having cores for that particular diameter is placed in the set of holes 9 in table 8. Since bushings of a particular size may be employed for marking

studs of various lengths within limits, studs of the same diameter but of various lengths within those limits will require no change of bushings.

The bushings 3, upon rotation of table 8, carry the studs 4 for marking between the upper and lower dies 21 and 22. The dies are mounted in alignment with the bushing 23 and stud 24 which are positioned closest to the frame 5 of the base 2 by the ball detent seats 15.

The ball detent seats 15 should be of sufficient number and so arranged that, after each of the successive rotational movements provided table 8, the balls 10 will enter corresponding seats 15 and secure the table 8 in position where a corresponding stud 4 is in the position of stud 24 between the dies 21 and 22 for stamping.

The upper die 21 is mounted a substantial distance above table 8 on bracket 25 secured to frame 5. The die 21 is removably secured to mounting bracket 25 at the top and extends downward so that its face is fixed a small distance for clearance above the upper end of the stud 24 to be stamped.

The lower die 22 is carried beneath table 8 and is provided with the stamping movement which effects the marking of the studs 4. In the retracted position the face of the die 22 rests beneath the table 8 in hole 26 drilled in the indexing table 14. In stamping, the die 22 moves vertically into the bushing 23, engages and pushes the stud 24 upwardly until its upper end strikes the upper die 21. The resilient impact or pressure of the dies 21 and 22 upon the stud then effects the marking of the stud 24.

The body of die 22 is cylindrical for inserting the die through hole 26 in the indexing table 14 and removably seating the die on mandrel 27.

Mandrel 27 is slidably mounted beneath the indexing table 14 on the supporting bracket 16. In the drawings the mandrel 27 has a cylindrical shape and slides within the hole 28 drilled in bracket 16 and in alignment with hole 26 in the indexing table 14.

The lower die 22 is moved upward and downward for stamping by the air or hydraulic cylinder 29 mounted on the rear of the frame 5. The plunger rod 30 of the air cylinder 29 is connected to the mandrel 27 by lever 31 and link 32. Lever 31 is pivotally mounted on the bracket support 16 at one end, extends through the aperture 33 in frame 4 and is connected to plunger rod 30 at its other end. Link 32 connects the mandrel 27 with lever 31.

The cylinder 29 is operated by compressed air through pipe 34 and two-way valve 35 from a source not shown. The cylinder 29 may be either of two-way operation or of one-way operation against a spring, and should be of sufficient capacity to effect the required stamping.

The rotational movement of table 8 is effected by pawl 36 slidably supported on the frame 5 by any suitable means such as the slide rod 37 and engaging the notches 38 in the circumference of table 8. The slide rod 37 is mounted on frame 5 alongside the table 8. The notches 38 are evenly spaced about the circumference of table 8 and should correspond with the holes 9 of table 8 so that with each reciprocal movement of pawl 36 the table 8 is moved from one ball detent position to the next and successive articles are positioned between the dies 21 and 22 for stamping.

The intermittent rotation of table 8 by pawl 36 and the intermediate stamping actions of the air cylinder actuated by air valve 35 are effected and also coordinated by two cranks 39 and 40

mounted on shaft 41 and connected to pawl 36 and air valve 35 by the connecting rods 42 and 43, respectively.

The shaft 41 is mounted behind the frame 5 of base 2 and opposite table assembly 1 and is driven by an electric motor 44 through the pulley drive 45, clutch 46 and gear box 47.

The connecting rods 42 and 43 each have a slideable bearing 48 secured by stop nuts 49 which permit selective adjustment of their lengths. Rod 42 extends through an aperture 50 in frame 5 of base 2 to connect crank 39 with pawl 36. Rod 43 connects crank 40 with the air valve 35.

Crank 39 and 40 are adjusted relatively on shaft 41 so that just after pawl 36 has engaged and rotated table 8, the air valve 35 is moved to the position for actuating the air cylinder 29 to effect the stamping of a stud, and while pawl 36 returns to the original position air valve 35 is moved to effect retraction of the lower die 22 prior to the next forward movement of pawl 36.

If desired, the machine may be equipped with an air or hydraulic cylinder effecting the stamping only, while the retraction of the die is effected by spring means not shown in the drawings.

The operation of the machine proceeds at a rapid rate and requires split-second timing. Any adjustments which may be required are easily made simply by adjusting the relative positions of the cranks 39 and 40 on shaft 41 and adjusting the rods 42 and 43 by means of stop nuts 49. The rate of operation is changed without interfering with the above adjustments by simply changing the speed of rotation of shaft 41.

The stamping action of the air cylinder provides a uniform impact of the dies on the work and ensures impressions made therein of the desired depth notwithstanding substantial variations in the size of the work.

Adjustments for marking studs or bolts of a different size are easily made. The lower die may be removed simply by lifting it from the mandrel. The upper die is accessibly mounted for easy replacement above the rotational table. The bushings are replaced simply by lifting them from the table and seating others of the required size within the holes.

A wide variety of articles other than bolts or studs and of different shapes and sizes within limits may be marked simply by providing suitable bushings or fixtures therefor for carrying the articles.

Either the upper or lower die may be blank where only one marking is desired.

Only one operator is needed to feed the machine by dropping the articles into the bushings on one side of the table and the marked articles are automatically dropped through the table as they are carried to the other side of the table. The table is set forwardly of the machine and is fully accessible for ease of operation.

Various embodiments of the invention may be carried out within the scope of the accompanying claims.

I claim:

1. A machine for stamping studs, bolts and the like comprising a base, a horizontal table supported by said base forwardly thereof for supporting the work, a rotatable member above said table having a plurality of spaced vertical holes circumferentially of the center of rotation to receive and carry the work supported by said table, ball detent means between said table and rotatable member constituting a bearing support

for said member during rotation of the latter upon said table, said detent means cooperating with said table to index said rotatable member and hold successive work pieces in a selected position for stamping, and a set of dies on said base disposed to operate and stamp at least one end of the successive work pieces.

2. A machine of the class described comprising a horizontal table, a rotatable member mounted above said table having a plurality of spaced vertical holes arranged circumferentially of the center of rotation thereof, spring detent means engaging said table and constituting the principal support for said member upon said table, said detent means cooperating with said table to index said rotatable member to correspond to said spaced holes, and power means to intermittently rotate said member to successive positions.

3. A machine for stamping studs, bolts and the like, comprising a base, a horizontal table supported by said base for supporting the work, fixtures to receive the work and carry the same upon said table between loading and stamping positions thereon, a rotatable member carrying said fixtures above said table, and spring detent means between said table and said member constituting the sole support for the latter and said fixtures during rotation thereof, said detent means cooperating with said table to index said rotatable member and hold said fixtures successively in said loading and stamping positions.

4. A machine of the class described comprising a base, a fixed horizontal table supported by said base, a shaft extending vertically from said table, a member mounted for rotation on said shaft above said table, spring means carried by said member and constituting the major support for the same upon said table, an abutment on said shaft securing said spring means in positive operative engagement with said table, fixtures circularly interspaced about said shaft to receive and carry work pieces to and from a given working position, and detent seats in said table engaged by said spring means and cooperating therewith to index said member and hold successive work pieces carried by said fixtures in said working position.

5. A machine for stamping studs, bolts and the like comprising a base, a horizontal table supported by said base forwardly thereof for supporting the work, a rotatable member above said table having a plurality of spaced vertical holes circumferentially of the center of rotation to receive and carry the work supported by said table, detent means between said table and rotatable

member and constituting the principal bearing support for the member upon said table, said detent means cooperating with said table to index said rotatable member and hold successive work pieces in a selected position for stamping, a set of dies on said base disposed to operate and selectively stamp at least one end of the successive work pieces, and power means to rotate said member intermittently to said successive positions.

6. A machine of the class described comprising a base, a fixed horizontal table supported by said base, a shaft extending vertically from said table, a member mounted for rotation on said shaft above said table, spring means carried by said member engaging said table and constituting the sole support for said member, an abutment on said shaft securing said spring means in positive operative engagement with said table, fixtures circularly interspaced about said shaft to receive and carry work pieces to and from a given working position, detent seats in said table engaged by said spring means and cooperating therewith to index said member and hold successive work pieces carried by said fixtures in said working position, a set of dies mounted on said base above and below said table and corresponding to said working position, and power means to rotate said member to move successive work pieces into said working position and to effect the uniform intermittent stamping action of said dies.
